UNITED STATES PATENT OFFICE.

DAVID ANDERSON, OF LONDON, ENGLAND.

BOTTLE SEALING.

Application filed September 6, 1923. Serial No. 661,233.

To all whom it may concern:

Be it known that I, DAVID ANDERSON, a subject of the King of Great Britain, residing at Westminster, London, England, have invented certain new and useful Improvements in Bottle Sealing, of which the following is a specification.

This invention relates to sealing devices for bottles and other containers of the class 10 in which a metal cap or casing carries a thin cork disk adapted to come in contact with the open end of the bottle or other container. Usually a lining of prepared paper is interposed between the cork and the metal 15 in order to perfect or improve the seal, but all cork disks used for the purpose above mentioned are far from being air tight or gas tight inasmuch as there is always present in cork-wood imperfections of various 20 kinds, such as natural pores, pin holes, interstices, cracks, crevices, or notches, hence it has been necessary to supplement the cork disks by the use of layers of prepared paper or the like.

25 Ordinarily the cork disks are prepared by stamping them out from sheets of cork-wood of the desired thickness and it has been found that a very large percentage of the disks thus made are filled to a greater or less extent with pores, pin holes, cracks, 30 crevices, etc., which renders them unfit for sealing purposes, and such disks are separated from the better grades and ground for use in various ways, such for instances, as 35 the manufacture of linoleum, or in the manufacture of composition sealing disks.

Nothing better than cork has yet been obtained for sealing purposes in the crown disks now so extensively used in the sealing 40 of bottles containing soft drinks, beer, and other liquids, as the cork is somewhat elastic and for the most part air tight and gas tight.

It is the object of my invention to so 45 treat the cork-wood that its imperfections may be eliminated. This I do by filling or closing the pin holes and other imperfections by small grains or particles of natural cork. To do this I may combine granulated 50 cork with a suitable binder or cementing agent to make the granules on their outer surfaces somewhat adhesive so that they will tend to adhere to each other to a certain extent and when the composition in this 55 condition is placed in the pin holes or imperfections, these imperfections will be com-

pletely closed and the cork granules will be firmly held therein.

There are several ways of carrying out my invention. According to one method, the 60 pin holes and other imperfections in cork disks are filled or closed by particles of cork in the manner above specified. As is well known to those in this art, cork in disk form is placed on the market in large quantities and supplied to manufacturers of bottle stoppers. A large percentage of such disks have various imperfections in them and are unsuitable for sealing purposes and are rejected by stopper makers, and are rejected by the makers of such disks and are not furnished to the stopper makers. Furthermore, the disks that are supplied to the stopper makers are in many instances imperfect. Large quantities of disks which 70 have not been rejected by the disk makers are received by the stopper makers and must be separated and regraded from the disks that are more perfect.

The filling material which I employ is 80 made by combining natural cork in a granulated form with a suitable binder. This binder may consist of albumin combined with glycerine or China wood oil, or corn oil, but other similar or suitable binders may 85 be used. Resinous binders are, however, not preferred and finely powdered or pulverized cork is preferably not employed, the particles of cork usually being of such size as to be quite distinct in the mixture. The 90 ingredients should be such as to not in any way impair the contents of the container.

When the composition is applied to cork in disk form, the disks in their natural state may be passed through suitable machinery 95 to separate or spread them in suitable condition for treatment and the composition is then applied to the disks in such manner as to close the openings or imperfections therein. The machinery can, of course, be 100 such as to carry the disks thus treated to suitable apparatus for drying and setting the fillings.

Another way of eliminating the imperfections in the cork disks is to apply the filling 105 material to sheets of cork of disk thickness by spreading the composition either on one side or on both sides if desired. After the application of suitable pressure the imperfections in the sheet will have been closed 110 or removed, and the surplus material may be wiped off and then after being dried the

disks may be cut from the sheet in the usual way.

It is found that in this way all the objectionable pin holes and other imperfections are completely closed and that practically all disks cut from the sheet are suitable for use.

Experience has demonstrated that cork disks with the imperfections removed in the manner above described are completely air tight and gas tight. It is not absolutely necessary that paraffin paper or the like be interposed between the cork disks and the metal cap although it may be used if desired.

The same methods may, of course, be applied to gaskets or rings used for sealing purposes.

Even when the disks are made from compositions containing cork and a binder, pin holes or other imperfections are often found in such disks, and my invention may be applied to disks made of such cork compositions.

In the accompanying drawings I have illustrated diagrammatically how my invention may be carried out in a practical way.

Figure 1 is a sectional view of a bottle sealing stopper of well known construction and extensively used.

Figure 2 is a perspective view of a cork disk showing various imperfections therein.

Figure 3 is a sectional view of such a disk showing more clearly certain imperfections that are often found in such disks, and illustrating how these imperfections may be eliminated by closing the pin holes and other openings therein. In Figure 3 the filling material is shown as being spread on opposite sides of the disk.

Figure 4 indicates the appearance of a disk after the surplus material has been removed.

Figure 5 is a plan view illustrating diagrammatically a sheet of cork with disks scored out therein.

Figure 6 is a sectional view of a sheet of cork indicating the disks with pin holes or imperfections therein and also shows how a layer of the composition of ground cork or granular cork and a binder may be spread on the sheet to fill or close the imperfections.

Inasmuch as the disks when completed are made solely from cork with a very small amount of binder, they are for practical purposes the same as natural cork throughout and free from imperfections.

One of the preferred ways of carrying out the invention is to use cork for filling purposes in a granular form with the par-

ticles separately impregnated or coated with the adhesive or binder so that when a layer of the material is spread on the disks or on the sheet of cork and pressure is applied in some suitable way, the particles of cork with a small amount of adhesive thereon will be sunk into the holes or crevices and close them.

Inasmuch as the pin holes, crevices, and other imperfections in the cork are often of different sizes, in order to most efficiently close all such openings it may be desirable to treat the cork with the composition in several steps, the larger openings being closed by granulated cork of comparatively large size, while the smaller openings may be progressively filled or closed by granulated cork of smaller size conforming to the sizes of the openings.

In any case the sealing disk when completed, while having its cavities and escape openings filled with granulated cork and a binder has the large area on both sides of the disk uncovered or exposed. I do not contemplate leaving a layer of granulated cork and a binder on either the upper or the lower side of the disk.

I claim as my invention:

1. A sealing disk of natural cork, having its cavities and escape openings of relatively small area filled with granulated cork and a binder while the relatively large area of natural cork on each side of the disk is uncovered or exposed.

2. A sealing disk of natural cork, having its cavities and escape openings of relatively small area in the body and edge of the disk filled with granulated cork and a binder, while the relatively large area of natural cork on each side of the disk is uncovered or exposed.

3. The method of making sealing disks which consists in filling the cavities and escape openings of relatively small area in the disks with granulated cork and a binder and in leaving the relatively large area of natural cork on each side of the disk uncovered or exposed.

4. The method of making sealing disks which consists in filling the cavities and escape openings of relatively small area in the disk with individual granules of natural cork and a binder and in leaving the relatively large area of natural cork on the upper and lower sides of the disk uncovered or exposed.

In testimony whereof, I have hereunto subscribed my name.

DAVID ANDERSON.
